CLAIM

The ornamental design for a smart swim goggle with embedded camera, as shown and described.

DESCRIPTION

FIG. 1 is a front perspective view of a smart swim goggle with embedded camera showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines depict portions of the smart swim goggle with embedded camera in which the design is embodied that form no part of the claimed design.
